EX

No. 12,702

Jan. 24, 1882

UNITED STATES PATENT OFFICE.

WALTER M. CONGER, OF NEWARK, NEW JERSEY.

DESIGN FOR A TEA-TRAY.

SPECIFICATION forming part of **Design No. 12,702**, dated January 24, 1882.
Application filed June 18, 1881. Term of patent 14 years.

To all whom it may concern:

Be it known that I, WALTER M. CONGER, a citizen of the United States, residing in the city of Newark, county of Essex, and State of New Jersey, have invented a new and useful Improvement in Designs for Tea-Trays and Waiters, fully described and represented in the following specification and the accompanying photograph, forming a part of the same.

10 The design is shown in the fac-simile annexed, in which is shown an elliptical tray having a flange turned upwardly and outwardly all around its edge. Inside the flange, upon the bottom of the tray, is shown a band 15 of light color, decorated by a continuous row of pointed ovals in darker color, each oval having in its center a leaf of three points. The flange is divided into panels by twelve pairs of lines crossing one another obliquely, the 20 lines being shown dark upon a light ground, and their inner and outer ends being joined by the inner and outer boundary-lines of the panels. The cross-lines have their four open angles enameled by radial dashes of color, 25 and the center of each panel is decorated by a symmetrical scroll design having a dot in the center with a few dashes of color above and below it. A bracket of double-ogee form is placed in the ends of each panel to inclose the 30 dashes of color around the cross-lines, and the terminal lines of the brackets are joined by a narrow line close to the margin of the panel at its inner and outer sides. The panels upon the flange are separated from the pointed ovals 35 upon the bottom of the tray by a narrow line of color, outside of which is a continuous row of small spots or dots. The fac-simile was photographed from a tray decorated in black and white to secure a good print; but as it is 40 the form of the design and not the color that is claimed, it is obvious that it may be pro-

duced in any harmonious colors. Thus the flange and the band upon the bottom of the tray may be blue, with black panel-lines and crimson ornaments; or the ground may be silvered and the various lines drawn in black and white, with blue ornaments.

The decorations upon the band at the bottom of the tray are immaterial to the design, as well as the band itself, the essential feature 45 being the division of the flange into panels by obliquely-crossing lines, as herein described. The flange being viewed obliquely in the photograph, the angle at which the lines appear to cross one another is somewhat distorted, as 50 well as the shape and ornaments about the panels, which are all foreshortened.

The precise number of panels employed is not material, provided the effect produced is retained; and it is obvious that the design is 55 equally applicable to round and square trays, as to the oval shape shown in the fac-simile.

Having thus defined my design, I claim the same as follows:

1. The design for a tea-tray, as herein shown 65 and described, consisting of the panels upon the flange, the same having their ends formed and united by obliquely-crossing lines, substantially as herein set forth.
2. In combination with the panels formed 70 upon the flange, as described, the band of color upon the bottom of the tray, and the pointed ovals delineated thereon, as herein shown and described.

In testimony whereof I have hereunto set my 75 band in the presence of two subscribing witnesses.

WALTER M. CONGER.
